(57) **CLAIM**

The ornamental design for a control button arrangement for a TV receiver, as shown and described.

DESCRIPTION

FIG. 1 is a top front perspective view of a control button arrangement for a TV receiver showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged detail view of the front elevational view as shown in FIG. 2, the rear elevational view as shown in FIG. 3 being a mirror image thereof;

FIG. 9 is an enlarged detail view of the top front perspective view as shown in FIG. 1;

FIG. 10 is an enlarged detail view of the right side elevational view of FIG. 5; and,

FIG. 11 is an enlarged detail view of the top plan view of FIG. 6, the bottom plan view being identical thereto.

The broken lines depict environmental subject matter only and form no part of the claimed design.
